UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-BURNER.

1,343,673.

Specification of Letters Patent. Patented June 15, 1920.

Application filed January 15, 1919. Serial No. 271,198.

To all whom it may concern:

Be it known that I, RUDOLPH HOFFMAN, a citizen of the United States, residing at Kankakee, in the county of Kankakee and

5 State of Illinois, have invented certain new and useful Improvements in Oil-Burners, of which the following is a specification.

The invention relates to oil heaters, and more particularly to burners therefor of the 10 type comprising a tubular wick mounted for vertical movement between inner and outer wick tubes and supporting a head or flame spreader, the latter being guided for vertical movement with the wick by a central 15 guide bar; and the primary object of the invention is to provide improved means for limiting the upward movement of the flame spreader and thereby of the wick, which is adapted, upon a simple movement of the 20 spreader, to permit the removal of the spreader from its support.

In the present instance, this object of the invention is attained by what may be termed a head - and - slot - connection between the 25 flame spreader and its guide bar. The slot is formed in the top plate of the spreader and the head is formed on the upper end of the guide bar which is secured at its lower end to the inner wick tube, the parts being 30 so arranged with reference to each other that in the normal position of the spreader its upward movement is limited by the head, but when the spreader is twisted slightly in one direction it is capable of detachment.

35 In the accompanying drawings wherein I have illustrated a preferred embodiment of the invention, Figure 1 is a central vertical sectional view through the upper portion of the wick tubes of an oil burner and 40 showing a flame spreader supported in normal or operative position upon the wick. Fig. 2 is a vertical sectional view taken on line 2-2 of Fig. 1, but showing the spreader at the upper limit of its movement. Fig. 3 45 is a fragmentary top plan view showing the parts in the position shown in Fig. 1. Fig. 4 is a similar view of the spreader detached from its support. Fig. 5 is a horizontal sectional view through the spreader taken in 50 the plane of line 5-5 of Fig. 1.

Referring to the drawings, 7 and 8 are respectively the inner and outer wick tubes of a burner, between which tubes a wick 9 is mounted for vertical movement by suit-

able and well known means (not shown). 55 10 indicates generally the flame spreader guided for vertical movement upon the wick 9 by the flat bar 11 fixed with reference to the wick tubes and extending through an opening 12 in the top of the 60 flame spreader, the upper end of the bar being provided with a head 13.

The wick tubes 7 and 8 are spaced apart in the usual way to provide a channel for the wick 9; and the spreader 10 may comprise a supporting member 14, a perforated drum 15, and a top plate 16. The bottom of said supporting member is in the form of an open plate or spider 17, while the lower end of the drum 15 is open so that 70 air may pass through the spider upwardly into the drum. At its upper end the supporting member has an annular wick flange 18.

The guide bar 11 is fixed with reference 75 to the wick tube 7 centrally thereof by means of a pair of perforated plates 19 and 20 spaced apart a short distance and suitably secured to the tube 7. Herein said plates are flexed away from each other at 80 their centers and their peripheries are entered in grooves formed by pairs of annular beads 21. The lower end of the guide bar is entered through central slots provided in said plates and it will be evident 85 that when fixed therein, as by soldering, the bar is firmly held against vertical movement relative to the tube 7 in either direction.

At its upper end the guide bar is cut out at its opposite edges to form a neck 22 which 90 carries the head 13. Said neck is twisted slightly to cause the head to be disposed in a different vertical plane from that of the bar proper. The opening 12 for the guide bar is of an irregular shape and may be 95 described as consisting of two slots 23 and 24 disposed transversely of each other. The slot 23 in which the guide bar normally operates is made of a length substantially equal to the width of the guide bar, while 100 the slot 24 is formed by notching the opposite side edges of the slot 23 and is made of a length corresponding to the width of the twisted neck portion 22. It will be seen that in the normal movement of the spreader 105 upon its support the guide bar proper will operate in the slot 23, and that the neck portion of the guide bar will operate in

the slot 24, the slots 23 and 24 being so disposed relative to each other as to correspond with the relative positions of the guide bar proper and the neck portion thereof. The head 13, however, being normally disposed in the plane of the slot 24 and being of a width greater than the length of said slot, will be engaged in the upward movement of the spreader by the top plate 16 thereof at the opposite ends of the slot, and thus will limit the upward movement of the spreader.

When it is desired to detach the flame spreader from its support upon the wick 9, it will be evident that it is only necessary to twist or turn the spreader slightly, when at the upper limit of its movement, in order to carry the slot 23 into the vertical plane of the head 13. Thereupon the spreader may be withdrawn, the head passing freely through the slot 23. For the purpose of enabling the turning or twisting movement of the spreader, the spider 17 at the bottom thereof is provided with a central opening 17^a which is enlarged at its opposite ends (Fig. 5) to permit the swinging movement of the guide bar therein.

In order to facilitate the operation of detaching the spreader from its support, the guide bar is provided with a central guide rod 25 which is circular in cross-section, and the opening 12 is shaped at its center to neatly receive said rod. It will be seen that during the passage of the neck portion of the bar through the opening 12, and especially when the spreader is being twisted to permit a withdrawal thereof, the rod coöperating with said opening prevents any lateral movement of the bar which might occur in the opening by reason of the differences in the length of the opening and the width of the neck portion. The rod may be mounted in the guide bar in any suitable way. Herein the bar is provided with a central slot 26 of a length somewhat less than the length of the rod and the opposite ends of the rod are provided with slots 27 and 28 for engaging the bar at the opposite ends of the slot 26. One of the slots, herein the slot 28, is made of a depth sufficient to enable the insertion of the rod into position in the slot 26, and after the rod is in position the walls of the slot 28 may be bent inwardly, as at 29 (Fig. 2) to prevent a removal of the rod from the bar. As can be seen from Fig. 5, the opening 17^a, in the spider 17, is also shaped to permit the passage of the rod 25 therethrough.

It will be seen that I have provided means for limiting the upward movement of the wick of an oil burner, which is of a very practical character. The construction is very simple, as is also the operation of releasing the spreader from its position

upon the supporting wick. Furthermore, the parts are of such a character as to be practically unaffected by the heat from the burner, and there are no loose parts to become disarranged or lost.

70

I claim as my invention:

1. In an oil burner, a wick, means for guiding the wick including a tube, a flame spreader carried by the wick and having a top plate, and a guide bar for said spreader mounted centrally of said tube and having a twisted neck portion at its upper end and a head on said neck portion disposed in a plane transversely of the bar, said top plate having a pair of transverse slots therein, one for said neck portion and one for said head portion, said slots being adapted to permit the bar and neck to pass therethrough and permitting a passage of the head therethrough after the spreader has been turned through a fixed arc of movement.

2. In an oil burner, a wick, means for guiding the wick including a tube, a flame spreader carried by the wick and having a top plate, and a guide bar for said spreader mounted centrally of said tube and having a head on its upper end disposed in a plane transversely of the bar, said top plate having a slot therein through which the bar is arranged to pass in the normal movements of the spreader, and said head being adapted to normally engage with the top plate to limit the upward movement of the spreader but permitting the detachment of the spreader after it has been rotated through a definite arc of movement.

3. In an oil burner, a wick, means for guiding the wick including a tube, a flame spreader carried by the wick and having a transverse plate, a guide bar for said spreader mounted centrally of said tube, and a connection between the spreader and guide bar comprising a head on the bar and a slot in said plate for receiving the head, said head and slot coacting to normally limit the upward movement of the spreader but permit a withdrawal thereof when the spreader is given a definite movement out of its normal position.

4. In an oil burner, a wick, a flame spreader carried by the wick and having a transverse plate, a guide bar for said spreader having a head on its upper end disposed in a plane transversely of the bar, said plate having a slot therein through which the bar is arranged to pass in the normal movements of the spreader, and said head being adapted to normally engage with the plate to limit the upward movement of the spreader but permitting the detachment of the spreader after it has been rotated to bring its slot into register with the head, and a guide rod carried by the bar and engaging with said plate to prevent a

125

130

lateral movement of the spreader relative to the bar during the rotation of the spreader.

5. In an oil burner, a flame spreader, a fixed guide bar for said spreader, and a connection between said guide bar and spreader comprising a head on the bar and a part on the spreader having a slot with which said head is adapted to coact to permit of a limited vertical movement of the spreader and releasable by a movement of the spreader relative to the guide bar.

6. In an oil burner, a flame spreader, a fixed guide bar for said spreader, and a connection between said guide bar and spreader comprising a head on said bar and a slot in said spreader, said head being normally disposed in the path of movement of the spreader but adapted to pass through the slot when the spreader is moved bodily out of its normal position.

7. In an oil burner, a flame spreader, a fixed guide bar for said spreader, a connection between said guide bar and spreader comprising a head on said bar and a slot in said spreader, said head being normally disposed in the path of movement of the spreader but adapted to pass through the slot when the spreader is rotated through a fixed arc of movement, and means for preventing the lateral movement of the bar in said slot during the rotation of the spreader relative thereto.

8. In an oil burner, a flame spreader, an upright stationary member adapted to guide the spreader in its up and down movement, and a connection between said spreader and said member adapted to permit of a limited vertical movement of the spreader and releasable by a rotation of the spreader relative to said member through a fixed arc of movement.

9. In combination with a plate member and a bar member, one of said members being movable and the other stationary, a connection adapted to permit of limited relative movement between said members comprising a pair of slots in the plate mem-

ber extending transversely of each other and one being of greater length than the other, a twisted neck on the bar member, and a head on said neck of a width substantially equal to the length of the longer slot but normally disposed in the plane of the shorter one of said slots, the parts being relatively movable to cause the head and the longer one of said slots to lie in the same plane.

10. In combination with a plate member and a bar member, one of said members being movable and the other stationary, a connection adapted to permit of limited relative movement between said members comprising a pair of slots in the plate member extending transversely of each other and one being of greater length than the other, a twisted neck on the bar member, and a head on said neck of a width substantially equal to the length of the longer slot but normally disposed in the plane of the shorter one of said slots, the parts being relatively movable to cause the head and the longer one of said slots to lie in the same plane and said bar member having a part coöperating with the plate member to prevent relative lateral movement between said members.

11. In combination with a plate member and a bar member one of which is stationary and the other movable, a connection adapted to permit of limited relative movement between said members comprising a slot in the plate member, a head on said bar member normally disposed in a plane extending transversely of said slot, the parts being relatively movable to cause the head and slot to be disposed in the same plane whereby to permit of a disconnection of the members, and a part carried by the bar member and coöperating with the plate member to prevent relative lateral movement between said members.

In testimony whereof, I have hereunto set my hand.

RUDOLPH HOFFMAN.
